(57) **CLAIM**

The ornamental design for a footwear carrier display, as shown and described.

DESCRIPTION

FIG. 1 is a perspective view of a footwear carrier display showing my new design;

FIG. 2 is a front view thereof;

FIG. 3 is a top view thereof;

FIG. 4 is a right side view thereof, the left side view being a mirror image thereof;

FIG. 5 is a back view thereof;

FIG. 6 is a bottom view thereof; and,

FIG. 7 is an environmental perspective view thereof. The broken lines showing the footwear, retention strap, and strap aperture are for the purpose of illustrating environmental structure and form no part of the claimed design.
